UNITED STATES PATENT OFFICE.

HUDSON MAXIM, OF HOPATCONG, NEW JERSEY.

EXPLOSIVE.

988,799.

Specification of Letters Patent.

Patented Apr. 4, 1911.

No Drawing.

Application filed October 22, 1907. Serial No. 398,669.

To all whom it may concern:

Be it known that I, HUDSON MAXIM, of the borough of Hopatcong, county of Sussex, State of New Jersey, have invented a 5 new and useful Improvement in Explosives, which invention is fully set forth in the following specification.

The present invention relates to improvements in explosive materials, particularly 10 what are known as detonative compounds; that is to say, compounds for detonating or exploding other high explosives, and also for igniting non-detonating high explosives such as gunpowder.

15 I have discovered that when finely pulverized or powdered metallic silicon or metallic calcium is mixed and thoroughly incorporated with red lead (oxid of lead) in proper proportions, a violently detonative 20 material is formed, which may be set off either by ignition or percussion, but which at ordinary temperatures and in the absence of friction may be kept for any desired length of time. At elevated temperatures, 25 however, the oxygen of the red lead attacks the metallic silicon or metallic calcium at the expense of the lead, and so much heat is liberated by the reaction that the lead is instantly thrown into a state of highly heated 30 vapor with detonative violence.

It is well known that when an oxid such as iron oxid is incorporated with powdered metallic aluminum and ignited, an enormous quantity of heat is evolved, so great being the 35 heat that this material, known as thermit, is utilized for welding steel rails and for other purposes where an enormously high temperature is needed to be localized on a given spot or limited area. But thermit is not explosive or detonative, for the reason that the 40 iron volatilizes at too high a temperature and the temperature of reaction is not sufficiently high to instantly volatilize the iron, although the iron is made boiling hot. 45 When, however, an oxid of a metal like lead, whose volatilizing point is much lower than that of iron, is employed, and where the heat of the reaction is still greater, all of the metallic lead set free by the reaction is thrown 50 into a state of highly heated vapor with explosive violence. I have found, also, that a mixture of sodium peroxid and finely pulverized metallic silicon produces a similar result, the oxygen of the sodium being given 55 up to the silicon with explosive violence.

As the detonative violence or detonative

efficiency of a detonator depends directly upon the weight or mass and temperature and volume of its products of combustion, it is necessary that the vapors or gases should 60 be propelled from the center of detonation with great velocity and violence; and I have found, therefore, that the addition of a small percentage of nitroglycerin or guncotton, or a colloid of nitroglycerin and guncotton, or 65 other explosive material capable of being resolved into gases, with also the evolution of a large amount of heat, adds materially to the detonative efficiency of detonators made according to my present invention. 70

In carrying out the invention I first mix and thoroughly incorporate the lead oxid and the pulverized metallic silicon, or calcium, as the case may be in the ratio, for example, of 80 to 90 parts of the former to 75 10 to 20 parts of either of the latter metals, and stir this mixture into a solution of about seven parts nitroglycerin to three parts gelatinized-pyroxilin or other form of guncotton formed with acetone or other suitable 80 solvent. The mass is then placed in a water bath and stirred until a sufficient quantity of the acetone has been evaporated to leave the materials in a pasty mass. These are then rubbed through a screen or sieve, placed 85 in a suitable dry - room or oven, and the residuary acetone is evaporated out; an agglutinated granular product is the result, capable, under warming and pressure, of being molded or compacted without danger 90 into detonators, or into any desired shape for use.

The proportions of the materials I prefer are about as follows: 85 to 90 parts of the mixture of oxid of lead and metallic silicon 95 or metallic calcium, and 10 to 15 parts of the mixture or compound of nitroglycerin and guncotton. The nitroglycerin and guncotton mixture being completely dissolved in acetone or other suitable solvent, permeates 100 all the spaces between the particles of the granular materials, and when evaporated as described, leaves all the particles of the lead oxid and the metallic silicon or calcium completely coated with a film of the nitro- 105 glycerin and guncotton colloid; that is to say, the particles are separated from one another and agglutinated by an elastic, rubbery, anti-friction substance, which renders the resultant compound very insensitive to shock and capable of being safely handled 110 and formed in the desired shapes. But as

- the colloid is itself a violently explosive material very easy of ignition, this new detonating material is capable of being very easily detonated by ignition, but is not very readily detonated by percussion, thus adapting it admirably as a detonative material for use in fuses for projectiles, for detonating insensitive high explosive bursting charges for the same. Furthermore, as the products of combustion of a guncotton and nitroglycerin colloid are almost entirely gaseous, and as the reaction of its combustion liberates a very large amount of heat, the gases of the colloid serve to propel the metallic particles of the lead set free by the reaction with very great violence against an adjacent explosive material required to be detonated. Furthermore, the ingredients of this detonative material being very much less expensive than fulminate of mercury and other fulminates, a very large saving of expense is realized from the use of the detonative material made according to my present invention. The resultant compound also may be safely handled at ordinary temperatures and employed in primers for igniting or detonating explosives for blasting and other purposes, as well as in cartridges for firearms.
- I do not desire to confine myself to the use of the red oxid of lead, as other metallic oxids, such as oxid of zinc, or a metallic peroxid such as sodium peroxid, may be employed.
- As the quantity of heat set free by the reaction of oxid of lead or peroxid of sodium with metallic silicon is so great, I may and sometimes do add a non-explosive body capable of evolving a large volume of gases by absorbing the heat of the reaction, for which purpose any suitable hydrocarbon such as paraffin wax, kerosene oil, or a light hydro-carbon like gasolene, or any suitable carbo-hydrate or oil may be used. I also may add a gas-producing ingredient, such as nitrate of ammonia, or a salt like carbonate of ammonia.
- What is claimed is:
1. An explosive compound consisting of a mechanical mixture of an oxid of a metal having a low point of volatilization and a powdered metal having at high temperatures a stronger affinity for oxygen than that of the metal of the oxid, and agglutinated with an explosive colloid containing nitrocellulose.
  2. An explosive compound consisting of a mechanical mixture of an oxid of a metal having a low point of volatilization and a powdered metal having at high temperatures a stronger affinity for oxygen than that of the metal of the oxid, and agglutinated with an explosive nitrated body.
  3. An explosive body consisting of an oxid of lead and silicon and an agglutinating body capable of the evolution of gases.
  4. An explosive compound consisting of a mechanical mixture of an oxid of a metal having a low point of volatilization and a powdered metal having at high temperatures a stronger affinity for oxygen than that of the metal of the oxid, ammonium nitrate and an explosive agglutinating body.
  5. An explosive body consisting of an oxid of lead and silicon agglutinated with an explosive colloid containing nitrocellulose.
  6. An explosive body consisting of an oxid of lead, silicon, ammonium nitrate and an explosive colloid containing nitrocellulose.
  7. An explosive compound consisting of a mechanical mixture of an oxid of a metal having a low point of volatilization and a powdered metal having at high temperatures a stronger affinity for oxygen than that of the metal of the oxid and agglutinated with an explosive nitrated body and a restraining substance which is capable of conversion into gases by the heat of the reaction of said metal and metallic oxid.

In testimony whereof I have signed this specification in the presence of two subscribing witnesses.

HUDSON MAXIM.
